UNITED STATES PATENT OFFICE.

WALTER SAWER YALE, OF BERWYN, ILLINOIS, ASSIGNOR TO WESTERN ELECTRIC COMPANY, INCORPORATED, OF NEW YORK, N. Y., A CORPORATION OF NEW YORK.

APPARATUS FOR AND METHOD OF WHIPPING STRAND ABOUT A CORE.

Application filed August 29, 1924. Serial No. 734,893.

To all whom it may concern:

Be it known that I, WALTER SAWER YALE, a citizen of the United States, residing at Berwyn, in the county of Cook and State of Illinois, have invented certain new and useful Improvements in an Apparatus for and Methods of Whipping Strand About a Core, of which the following is a full, clear, concise, and exact description.

10 This invention relates to an apparatus for and a method of whipping strand about a core, and more particularly to a method of and a mechanism for whipping telephone cords with strand material preparatory to 15 securing terminals thereto.

An object of the invention is to whip cores with strand material accurately, speedily, and with a minimum amount of manual labor.

20 In accordance with the general features of the invention there is provided means for withdrawing a predetermined length of wire from a supply spool and winding it on a bobbin which spirally whips it about the 25 end of a cord, positioned in the center thereof, the cord being moved along its axis the required distance for each turn of the wire wrapped or whipped on the cord.

Other objects and advantages of the invention will more fully appear from the following detailed description taken in connection with the accompanying drawings which illustrate a mechanism embodying the invention and in which drawings,

35 Fig. 1 is a side elevation of the whipping mechanism;

Fig. 2 is a plan view thereof;

Fig. 3 is a front view of the mechanism, a portion of which is fragmentarily shown 40 in section;

Fig. 4 is an elevation, partially in section, taken from the side opposite to that shown in Fig. 1 and showing a portion of the whipping mechanism;

45 Fig. 5 is a detail view of the bobbin which whips the wire about the cord;

Fig. 6 is a detail view of a resilient guiding and catching device thereof;

50 Fig. 7 is a detail view of the stationary member showing the hook for guiding the wire;

Fig. 8 is a view of the cord after it has been removed from the whipping mechanism, and

55 Fig. 9 is a diagrammatic view showing

the way the wire is laid on the end of the cord.

It is believed that the method of whipping a strand on cords will be readily understood from the following description of an apparatus by which it may be performed.

Referring now to the drawings in detail in which like reference numerals designate similar parts throughout the several views, 10 denotes a frame of the machine which 65 may be mounted on any suitable bench (not shown). A supply spool 12 of a wire 13 is (Figs. 1 and 2) rotatably mounted in brackets 14 and secured to the frame 10. Located to one side of the supply spool 12 70 is a pulley 16, keyed to a shaft 17, and driven by a belt 18 connected to any suitable driving means (not shown). Also splined to the shaft 17 is a pulley 19, which through a belt 20 drives a pulley 24 keyed to a shaft 75 25 (Fig. 4). Contiguous with the pulley 24 and likewise keyed to the shaft 25 is a cam 26, the cam surface of which is adapted to actuate a pin 27 pivotally secured at a point 28 to a bell crank lever 29 (Fig. 4), pivoted 80 at a point 30 to the frame 10. One arm of the lever 29 is bent upwardly in such a manner that its end 33 rides on top of a cord support 34 (Figs. 1 and 2).

The cord support 34 is reciprocably 85 mounted in the keyway 35 (Figs. 2 and 3). Formed on the cord support 34 is a member 36, the end of one arm 37, of which rides in a cam like surface 39 of a cam 40. Integral with the arm 37 is a pin 31, the end of 90 which passes through a hole 32 in the frame 10. Interposed between the member 36 and the frame 10 and surrounding the pin 31 is a compression spring 41. The cam 40 is keyed to a shaft 43 rotatably mounted in and 95 carried by a bracket 44 secured to the frame 10. Splined to the other end of the shaft 43 is a gear 45 which meshes with the gear 46 keyed to the shaft 17. Also keyed to the shaft 17 is a gear 47 which meshes with 100 another gear 48 which is integral with a rotatable circular member 49, both the gear 48 and the member 49 rotating about a stationary circular member 50 (Fig. 3).

Mounted on the rotatable member 49 is a 105 resilient guiding, wire catching and retaining device denoted generally by reference numeral 53 which consists of a round member 54, secured to a pin 55 (Fig. 6) which fits in a bore 56 in the member 49. Mounted 110

on the pin 55 are two washers 73 and 74. Surrounding the pin 55 and interposed between the washer 73 and the washer 74 is a spring 57 secured at one end to the washer 74 and at the other to the washer 73, which draws the member 54 inwardly against the surface of the rotatable member 49. Secured to the revolvable member 49 is a pin 58 which fits in a hole 59 in the member 54 and serves to prevent the round member 54 from revolving. Likewise, fastened to the member 49 is another pin 61 slightly beveled at its end 62 which fits in a hole 63 in the member 54 and serves to prevent the wire 13 from leaving the device 53.

Also attached to the rotatable member 49 is a small arm 60, the end of which is formed into a U-shaped guide 64. Extending through the stationary member 50 is a hole 65 in which is secured a U-shaped guide 66 formed similarly to the U-shaped guide 64; both of the guides being located at the center of the members 49 and 50 and the gear 48 (Fig. 6). Secured to the bottom of the forward part of the guide 66 is a hook 76, as shown in Fig. 7, which serves to properly guide the wire 13.

Integral with and surrounding the member 49 is a cap shaped element 67 (Fig. 5) which forms a bobbin denoted generally by reference numeral 71 and is provided with a slot 68. Positioned to the rear of the slot 68 and integral with the element 67 is a wing shaped member 69. Located between the member 49 and the cap 67 is an annular space 70 (Fig. 5) in which the predetermined length of wire is wound as will be more fully described hereinafter. It will be noted that the cord support 34 is provided with a V-shaped groove 72 which is in alignment with the guides 64 and 66.

The operation of this mechanism is as follows: The operator withdraws the wire 13 from the spool 12 and threads it through the hole 65 in the stationary member 50; the wire 13 passing through the center of the U-shaped guide 66, through the hook 76 and through the center of the U-shaped guide 64. The wire 13 is then drawn along the bottom of the groove 72 in the support 34 (Figs. 1 and 2) and over the end 33 of the lever 29. It is to be understood that before the machine is set in operation the operator must pull the wire 13 outwardly from the stationary member 50 until its end is in line with the end of the frame 10; the distance between the member 50 and the end of the frame 10 being approximately equivalent to the predetermined length of wire required for one whipping operation.

Upon the application of power to the belt 18, the cam 26 is caused to revolve through the pulleys 24 and 19 and the belt 20. The cam 26 actuates the pin 27 causing the lever 29 to pivot upon the point 30. The lever

29 in pivoting carries the wire 13, just laid on the end 33 of the lever upwardly, as shown by the dotted lines in Fig. 4, until the wire 13 is caught by the circular member 54 of the resilient guiding and catching device 53 secured to member 49 which is at this time rotating by means of the revolving gears 48 and 47. The wire 13 upon coming into contact with the member 54 slides between the member 54 and the face of the member 49 and over the beveled end 62 of the pin 61 assuming a position to the rear of the pin 61. The pin 61 prevents the wire 13 from flying out from under the member 54 and the pin 58 serves to prevent the member 54 from being turned by the wire 13. The wire 13 is then engaged by the wing 69 on the rotating member 49 which causes it to enter the slot 68 in the cap 67 (Fig. 5), and to be wound in the space 70 about the stationary member 50. The cap is of such a design that as soon as the wire is wound in the space 70 it permits the lever 29, through gravity, to fall back into its original position on the support 34. A cord 75 is then laid in and held in the groove 72 of the support 34 and on top of the end 33 of the lever 29 and with its end, to be whipped, lying in the guides 64 and 66, which support the cord centrally of the members 49 and 50 and on top of the wire 13. The member 49 in revolving about the stationary member 50 and the cord 75 whips the wire about the end of the cord. The wire 13 used for the whipping is withdrawn from the space 70 of the bobbin 71 and is guided by the device 53. The wire 13 in being whipped about the end of the cord is prevented from pulling the cord from its central position in the guide 66 by the guide 64 which revolves around with the member 49.

The cam 40 through the gears 45 and 46 is caused to revolve and its surface 37 is so designed that as soon as the whipping of the wire 13 about the cord 75 starts, the pin 37 is actuated which through the member 36 moves the cord support 34 outwardly causing the wire 13 to be whipped spirally around the end of the cord. The cord support 34 in being moved outwardly compresses the spring 41; and the end 33 of lever 29 rides along the top of support 34 under the cord 75.

When all of the wire has been withdrawn from the bobbin 71 and whipped about the end of the cord spirally, the operator pulls the cord outwardly, drawing the wire from the spool 12 with it until the whipped end of the cord is clear of the end of the support 34 at which time the wire is cut. The cam 40 is of such a design that it will cause the support 34 to be moved outwardly a distance just sufficient to permit the whipping of the end of the cord with the predeter-

mined length of wire, the removal of the cord from the support 34 and the severing of the wire, whereupon spring 41 is allowed to expand forcing the support to be returned to its original position.

The lever 29 is then set in motion by cam 26 causing the wire drawn outwardly by the support 34 and by the operator, which is the predetermined length of wire to be wound on the bobbin 71 as has already been described and the whipping operation is repeated.

What is claimed is:

1. In a mechanism for whipping the end of a core with strand material, means for releasably holding an end portion of strand of predetermined length and for whipping it about the core.
2. In a mechanism for whipping the end of a core with strand material, means for releasably holding an end portion of strand of predetermined length and for whipping it about the core, a support for the core, and means for causing a relative movement between the support and the first mentioned means to cause the strand to be whipped about the core.
3. In a mechanism for whipping the end of a core with strand material, an element for releasably holding strand material and for whipping the strand about a core end, and means for causing a strand end portion of predetermined length to be associated with said element.
4. In a mechanism for whipping the end of a core with strand material, an element for releasably holding strand material and for whipping the strand about a core end, a support for the core, means for causing a strand end portion of predetermined length to be associated with said element, and means for causing a relative movement between the support and the whipping means to cause the predetermined length of strand to be whipped about the core in spiral formation.
5. In a mechanism for whipping the end of a core with strand material, means for holding a strand supply, an element for releasably holding strand material and for whipping the strand about the core, means for guiding a predetermined length of strand from said supply to said element, a support for the core, and element for causing a relative movement between the support and the whipping means to cause the strand to be whipped about the core.

6. In a mechanism for whipping the end of a core with strand material, an end portion of strand of strand supply, means including a bobbin for taking up a predetermined length, and means for causing the predetermined length of the strand to be whipped about the core.

7. In a mechanism for whipping the end of a core with strand material, a support for the core, a strand supply, means including a bobbin for taking up an end portion of strand of predetermined length, means for whipping the predetermined length of strand around the core, and means for causing a relative movement between the support and the whipping means to cause the predetermined length of the strand to be whipped around the core in spiral formation.

8. In a mechanism for whipping the end of a core with strand material, means for holding a strand supply, means for retaining strand material, means for bringing a predetermined length of strand into engagement with the retaining means, and means for whipping the predetermined length about the core.

9. In a mechanism for whipping the end of a core with strand material, means for holding a strand supply, means for retaining a predetermined length of strand, means including a lever for bringing the predetermined length of strand into engagement with the retaining means, and means including a bobbin for taking up the predetermined length of strand and thereafter whipping it about the core.

10. A method of whipping the end of a core with strand material, which consists of withdrawing a predetermined length of strand material from a supply, storing the predetermined length of strand and thereafter whipping the stored strand about the core.

11. A method of whipping the end of a core with strand material, which consists of withdrawing a predetermined length of strand material from a supply, storing the predetermined length of strand, and causing a relative movement between the core and stored strand to cause the strand to be whipped about the core in spiral formation.

In witness whereof, I hereunto subscribe my name this 14th day of August A. D., 1924.

WALTER SAWER YALE.
